UNITED STATES PATENT OFFICE.

OTTO NELSON, OF HOLLYWOOD, CALIFORNIA.

SOFT-TIRE ALARM.

Application filed December 13, 1923. Serial No. 680,430.

To all whom it may concern:

Be it known that I, OTTO NELSON, a citizen of the United States, residing at Hollywood, in the county of Los Angeles and State of California, have invented new and useful Improvements in Soft-Tire Alarms, of which the following is a specification.

This invention relates to soft tire alarms and to a mechanical bell construction.

10 It is an object of the present invention to provide an improved bell hammer mechanism.

An object of the invention is to provide a simple and inexpensive form of alarm device adapted to be readily attached to the spoke of a wheel of a pneumatic tired vehicle, whereby to give an alarm when the tire becomes of an undesirable low pressure condition.

20 Other objects and advantages will be made manifest in the following specification of an embodiment of the invention illustrated in the accompanying drawings, wherein:

25 Fig. 1 is a side elevation of the device as applied to a wheel and tire; parts of the latter being in section.

Fig. 2 is a plan of the device applied.

Fig. 3 is a sectional view through the shell and bell mechanism and shows the working levers in elevation.

Fig. 4 is a section on line 4—4 of Fig. 3.

The present invention consists of any suitable bell 2 appropriately mounted as on a post 3 secured in a base 4, upon which is arranged a suitable gear train including a pinion 5. The pinion 5 is secured to a gear 6 and the latter engages a gear 7 on the post 3 which is also secured to a rotor 8 on the post.

40 The rotor is disposed contiguous to the bell 2 and is provided with one or more independent hammers 10, forming a feature of this invention. The rotor consists of any suitable frame or carrier including upper and lower plates 9 between which the hammers 10 are arranged substantially radially to the post 3 about which the rotor turns. The plates 9 of the rotor are connected by lugs 11 spaced from each other in pairs and forming in each pair an opening through which a hammer 10 is thrown to an outermost position by a centrifugal action when the rotor is turning. Each hammer is here 50 shown as substantially triangular in plan

and as having rear corner ears 12 positioned to engage the respective pair of lugs 11 when the hammer is thrown outward. The hammer in the normal position projects radially from the post 3 and in the carrier 60 8 and the outermost end of each hammer is designed to engage a projecting portion as a pin 15, fixed on the bell within which the set of hammers are shown positioned. The hammers are adapted to swing freely 65 inwardly when impinging the bell pin 15; one ear 12 of the striking hammer rocking as a pivot on the contiguous supporting lug 11, as is clearly shown in Fig. 4. As soon as the engaged hammer swings away from 70 the striking pin the hammer will be thrown outwardly again to its position by a centrifugal action of the rotor. It is understood that the hammers are thrown to their outer position without spring action or support, and they will be outwardly positioned 75 instantly upon the start of rotation of the rotor.

Various means may be employed for actuating the gear train of the bell, and such means is shown as consisting of a rack 16, the toothed edge of which is in engagement with the pinion 5. Reciprocation of the rack will cause the rotation of the pinion and of the rotor. Reciprocation of the rack 85 16 in either direction effects the ringing of the signal bell 2, since the several hammers 10 are operable in either direction of rotation of the rotor.

The soft tire alarm of the present invention includes a suitable lever arm 20 pivoted at 21 on a bracket 22, forming a part of an attaching means such as the plate 4. The plate is provided at one end with a clamp structure adapted to be closed around and 90 secured on a spoke S of the vehicle wheel, having a pneumatic tire T.

A clamp is shown as consisting of a pair of swinging jaw 24, the free ends of which may be drawn around a spoke and fastened 100 by a bolt 25.

In the present case the lever 20 is shown as extending down on one side of the tire T and when the tire bulges laterally to an undesirable degree as when it becomes under-inflated, the upper end of the lever becomes effective to sound a signal by the ringing of bell 2 mounted on the plate 4. In this case the bell is concealed in the shell 26 to protect it from mud and dirt; the shell 110

being provided preferably with screened apertures 26^a affording emanation of sound from the enclosed bell.

The bell will be sounded by the movement 5 of the rack 16 energizing the gear train of the bell. The lever is normally pressed against the side of the tire as for instance by a spring 20^a which may be coiled about the pivot 21 on which the lever is mounted.

10 As shown, one ear of the spring 20^a extends up through an aperture provided therefor in the outer end of the rack so that the rack is drawn out by the spring at the same time that the lever arm 20 is pressed inwardly against the side of the tire.

15 Further embodiments, modifications and variations may be resorted to within the principle of the invention.

What is claimed is:

20 1. In a signal bell, a rotor forming a chamber and providing spaced stops, and a bell striking hammer freely mounted in the chamber of the rotor and limited in an outward position by engagement with the said stops, said hammer being adapted to pivot on either of the stops when striking a bell part, the hammer being provided with a pair of ears engaging the said stops in the outermost position of the hammer while the 25 rotor is rotating.

25 2. A soft tire alarm device comprising in combination, means adapted to be clamped to a part of a wheel provided with a pneumatic tire and including a bell, means for striking the bell to produce a sound signal, and a lever arm pivotally mounted and extending downwardly into engagement with the tire and operating the bell-striking means when the tire bulges laterally unduly, said 30 bell-striking means including an element extending laterally to be engaged by the lever when swung by the tire.

35 3. A soft tire alarm device comprising in combination, means adapted to be clamped to a part of a wheel provided with a pneumatic tire and including a bell, means for striking the bell to produce a sound signal, a lever arm pivotally mounted and extend-

ing downwardly into engagement with the tire and operating the bell-striking means 50 when the tire bulges laterally unduly, said bell-striking means including an element extending laterally to be engaged by the lever when swung by the tire, and a spring for normally pressing the lever against the tire. 55

4. A soft tire alarm device comprising in combination, means adapted to be clamped to a part of a wheel provided with a pneumatic tire and including a bell, means for striking the bell to produce a sound signal, 60 a lever arm pivotally mounted and extending downwardly into engagement with the tire and operating the bell-striking means when the tire bulges laterally unduly, said bell-striking means including an element extending laterally to be engaged by the lever when swung by the tire, and a spring for normally pressing the lever against the tire, 65 said spring being connected to the said member to draw the same outwardly.

5. A soft tire alarm device having a clamp to engage a spoke of a wheel to hold the device against the inner face of a felly having a rim provided with a pneumatic tire, 70 said device including a bell means for striking the bell to produce a sound signal and including a train of gears, a lever arm pivotally mounted and extending into engagement with a tire, and a gear rack connected to the lever arm and engaging one of the gears 80 to operate the bell when the tire becomes soft.

6. A soft tire alarm device comprising a frame adapted to be mounted against the inner face of a felly carrying a rim and 85 pneumatic tire, a bell upon the frame, a gear train having hammers for hitting the bell, a gear rack engaging one of the gears and extending laterally, a lever pivotally mounted and connected at one end to the 90 gear rack and having the other end bearing upon the side of the felly.

In testimony whereof I have signed my name to this specification.

OTTO NELSON.
